UNITED STATES PATENT OFFICE.

JOHN E. FEFEL, OF PHILADELPHIA, PENNSYLVANIA, ASSIGNOR TO UNITED STATES FELLING MACHINE COMPANY, A CORPORATION OF NEW YORK.

BLINDSTITCHING SEWING-MACHINE.

No. 861,821.

Specification of Letters Patent.

Patented July 30, 1907.

Application filed March 9, 1906. Serial No. 305,032.

To all whom it may concern:

Be it known that I, JOHN E. FEFEL, a citizen of the United States, residing at 240 South Ninth street, Philadelphia, county of Philadelphia, and State of Pennsylvania, have invented certain new and useful Improvements in Blindstitching Sewing-Machines, fully described and represented in the following specification and the accompanying drawings, forming a part of the same.

10 The present invention relates to that class of sewing machines which is employed in "felling" or making "blind stitches" upon one side of a fabric for attaching a lining, binding, or facing thereto; and in which a curved needle operates wholly upon one side of the 15 fabric.

In the present machine, the cloth or work-piece to be sewed is pressed upward by a feed-wheel against the flat under surface of the foot, which has a slot or throat therethrough, which permits the curved needle to enter 20 and emerge from the upper side of the cloth. The cloth therefore needs no bending to permit the operation of the needle, and the feed-table does not require any ridge or angular work-support over which the cloth can be bent. The machine is thus fully distinguished from those employing an angular work-support 25 extended lengthwise of the seam, as has been common heretofore. The machine is also distinguished by the provision of a raceway supported over the foot transverse to the path of the needle, with a shuttle reciprocated therein to engage a loop upon the upper side of the needle. The curved needle is mounted upon an oscillating carrier which is movable bodily sidewise so as to oscillate the needle in different parallel planes, the lateral movement of the carrier being variable so 30 that the needle may intersect the cloth upon alternate stitches at a greater or less distance apart, or may be oscillated continuously in the same position so as to stitch a straight seam, as in machines which are not adapted for blind stitching. The shuttle may be 35 pointed at one end, as is common, and reciprocated in the raceway once for each oscillation of the needle; or it may be pointed at both ends and operated to engage a loop of the needle-thread when moving in both directions; with this arrangement, the shuttle reciprocates 40 only one-half as often as the needle.

The double pointed shuttle and means of operating the same is made the subject of a separate application, entitled blind stitching sewing machine Serial No. 305,033, filed March 9, 1906, filed of even date herewith.

50 The present invention will be understood by reference to the annexed drawing, in which

Figure 1 is a side elevation of the machine; Fig. 2 is a side view of the head with the cover removed to expose the interior; Fig. 3 is a section of the head on line 3—3 in Fig. 2, with the connections from the driving-shaft to

the shuttle-carrier omitted; Fig. 4 is a cross section on line 4—4 in Fig. 1, showing the feed-gearing; Fig. 5 is a plan showing the feed-mechanism the feed-wheel being omitted; Fig. 6 is a diagram showing the shuttle operating with the needle above the surface of the cloth, the foot and raceway being omitted to show the threads clearly; Fig. 7 is an end view of the feed-arm and needle-carrier with section of the foot showing the needle operating upon the cloth; and Fig. 8 is a plan of the foot, shuttle and raceway. Fig. 9 is a face-view of the cog-wheel, carrying the cam g' , and Fig. 10 is a longitudinal section of the feed-arm adjacent to the feed-wheel.

The same reference letters are applied to similar parts herein, as in the co-pending application referred to.

The machine is shown with a frame having a hollow post A, goose-neck B and head C, with a driving-shaft D extended into the head.

Connections for needle-carrier. A rock-shaft G for the needle-arm or carrier a is shown mounted to turn, and also to reciprocate in a bearing below the driving-shaft. 75 A link c connects a crank upon the rock-shaft G with a crank upon the driving-shaft D, to oscillate the needle-carrier for each rotation of said shaft. The reciprocation of the rock-shaft G is for shifting the needle-carrier laterally, as is common in sewing zigzag stitches, and is 80 effected as follows: A stud E carries a gear F, which meshes with a gear F' upon the driving-shaft, and carries a grooved cam g' . This cam vibrates an arm e at each rotation of the driving-shaft, to oscillate a segment g having an adjustable pin f' which is linked by a ball-joint to the end of the needle rock-shaft G. The adjustment of the pin f' varies the lateral displacement of the needle n , as is required for sewing zigzag seams of various widths.

Foot and feed-table. A feed-arm H has one end jointed within the post A and is extended beneath the head C to carry the feed-wheel w beneath the needle-arm. A leaf-spring J presses the feed-arm normally upward, and a treadle O' and chain O are shown diagrammatically in Fig. 1 to depress the feed-arm for inserting the 90 cloth or fabric to be sewed beneath the foot M which is supported upon the head. An adjusting screw K is arranged beneath the spring to regulate the upward elastic pressure of the spring against the feed-arm, and the upward movement of the arm is regulated by a screw L 100 having an adjustable nut L' . The feed-table is shown flat upon the upperside, and the under side of the foot M is correspondingly flat, and a feed-wheel w is supported elastically upon the feed-arm which forms the table, so as to project normally above its surface and press the 105 cloth against the bottom of the foot, which is thus the sole guide for the movement of the cloth.

Shuttle connections. The raceway P for the shuttle is shown supported directly above the foot by means of legs r attached to the head, and is divided midway for 110

the passage of the needle, and to permit the loop of the needle-thread to project upwardly into the path of the shuttle Q. The shuttle is vibrated by a shuttle-carrier R and shuttle-arm R', having a pivot S' above and at 5 one side of the driving-shaft transverse to the same, and provided with a spherical crank-pin S². An eccentric I upon the driving-shaft is shown connected by link I' to the pin S², so that the shuttle is reciprocated or oscillated once at each rotation of the driving-shaft. The 10 feed-wheel adjusts itself, when material of different thicknesses is fed beneath the foot in the operation of sewing. The foot is supported upon the head by a vertically adjustable bar M' having screw N² to set the same to and from the needle-carrier and raceway; which 15 latter are adjusted in such a position that the under side of the needle, as shown in Fig. 7, just clears one corner of the shuttle. The shuttle is pointed wholly toward this corner, so as to readily pick up the loop j from the top of the needle. The foot is formed with a 20 throat or slot m which permits the curve of the needle to move a little below the under side of the foot, and thus penetrate the cloth close to the feed-wheel w. The feed-wheel in practice is made with marginal rows of teeth w and an intermediate smooth space w' which 25 may crowd the cloth close to the needle without interfering with the operation of the same, as shown in Fig. 10. A spring W is shown supporting the bearings of the feed-wheel elastically, so that it may yield independently of the feed-arm to suit various thicknesses of 30 cloth x. The upward pressure of the feed-arm, effected by the spring J, is regulated by screw J', which may be adjusted by the operator to suit the thickness and stiffness of the cloth beneath the foot.

Thread-guide and take-up. The needle is shown with 35 a vertical eye l (Figs. 6 and 7) and groove l' upon the under side, and the thread is led into such groove by a thread-guide p attached by the needle-arm or carrier close to the shank of the needle. An ear p' and a guide-arm p² upon the needle-carrier receive the thread 40 from a take-up lever V. This lever, as shown in Fig. 3, is actuated by a cam having groove v' engaged with a pin v upon the lever.

Feed-wheel driver. The feed-shaft h is extended from the feed-wheel w through the feed-arm into the post A, 45 where it is provided with a fine toothed ratchet-wheel b. An eccentric d is mounted upon the driving-shaft D over such ratchet-wheel within the post, and the eccentric strap is attached directly to a pawl c' which is adapted to reciprocate over one side of the ratchet- 50 wheel and is pressed normally toward the same by a spring k. An adjustable gage q is secured in the frame by a set-screw q', with its point at one side of the pawl. When the gage is retracted sufficiently, the pawl throughout its entire movement, engages the teeth of 55 the ratchet-wheel, but as it first strikes the ratchet-wheel upon the curved upper surface of the latter, the adjustment of the gage toward the pawl serves to press it slightly away from such curved surface and cause it to engage the ratchet-teeth at a later point in its de- 60 scent. Gage marks r are formed upon the gage q, which indicate the number of teeth which would be engaged by the pawl when the gage is correspondingly adjusted. A nut k' is applied to a thread upon a tightening rod for the spring k, and the pressure of the 65 pawl against the feed-wheel and the position of the

gage, are thus both adjustable. The gear-wheels F and F' are in the proportion of two to one, as shown in Fig. 9, and the cam g' is shaped to shift the needle-bar laterally before each forward movement of the needle reciprocates successively in different parallel planes, 70 and in each position forms a stitch with the co-operation of the shuttle. The needle-thread and the shuttle-thread, with this operation of the needle, form a double chain stitch, and show zigzag lines upon the surface of the cloth, as represented in Fig. 6. The needle moves 75 tangentially to the feed-wheel w and to the cloth which lies upon the wheel, as the needle does not pass through the cloth in forming the stitches, but enters and emerges from adjacent points upon the same side of the cloth, as is clearly shown in Fig. 7. A very simple 80 mechanism is thus used for operating the shuttle and forming a lock-stitch with the thread of the curved needle above the surface of the foot, and the use of a shuttle thus greatly improves this class of felling or blind stitch machine. 85

In Fig. 6, a single pointed shuttle is shown, but in Fig. 8, a double pointed shuttle is shown, which may, be reciprocated only half as often as the needle-carrier, because its points are adapted to engage the needle-thread when moved in both directions. 90

The double pointed shuttle and its connections are claimed in my co-pending application No. 305,033, filed simultaneously herewith, on March 9, 1906. 95

It is especially to be noted that the surface of the feed-arm in the present invention may be flat, as shown in Fig. 7, as well as the under surface of the foot, and that no ridge is required upon the feed-arm to bend the cloth or fabric at an angle, nor is the needle operated transversely to any such ridge, in order to pass in and out of the cloth upon the same side. Such passage of the needle is secured, in the present invention, by the use of the throat in the flat foot and the pressing of the cloth upward through the throat in the path of the curved needle. The needle is shown herein reciprocated at right angles to the path of the shuttle, and 100 transverse to the axis of the feed-wheel; but the needle may be operated at an angle to the axis of the feed-wheel or at any angle to the raceway which will permit the shuttle to engage the loop of the needle-thread. 105

The machine operates as follows: The cloth, with any 110 facing or attachment that is to be secured thereon is placed upon the flat feed-table which is lowered by pressing upon the treadle O' and when released clamps the cloth between the feed-table and the foot. If zigzag stitches are desired, the pin f' is adjusted in the 115 segment g to reciprocate the rock-shaft D to the required degree, and the needle thus alternately intersects the cloth upon two different lines, the shuttle engaging a loop of the needle-thread at each of the needle's movements, and the needle-thread and looper- 120 thread crossing one another upon the surface of the fabric, as shown in Fig. 6. The adjustment of the pin f' in the segment g determines the width of the zigzag stitches, and when the pin is carried up to the center of oscillation of the segment, it becomes stationary, the 125 needle-carrier a oscillates continuously in the same position, and the needle forms a straight row of stitches. The movement of the needle into the cloth is in the line of the seam, and not across the seam, and the width of the zigzag stitches is therefore dependent solely upon 130

the reciprocating movement of the rock-shaft G which oscillates the needle-carrier. In this respect, the machine differs widely from those in which the needle operates transverse to the line of the seam and in which 5 the width of the seam is governed by the penetration of the needle through the cloth. In such transverse movement of the needle, a greater width of seam can only be secured by penetrating the cloth to a greater depth, which is, of course, prohibited in sewing thin 10 materials; whereas, the present construction can form a zigzag seam of any width upon material of any thickness. Owing to the flat form of the feed-table which supports the cloth, and the width of the feed-wheel w which has teeth at its opposite edges, any part of the 15 cloth may be readily submitted to the needle, and a line of blind stitches can therefore be formed along the edge of the cloth to fasten a facing or thread thereto.

Having thus set forth the nature of the invention what is claimed herein is:

20 1. In a blind stitching machine, the combination, with the frame of the machine having a post, a goose-neck and a head carried thereby, and a feed-arm projected from the post beneath the head and provided with a flat feed-table, and feeding mechanism for propelling the cloth across the 25 flat-table transverse to the feed-arm, of a needle-bar upon the head carrying a curved needle, means for oscillating the needle transversely to the feed-arm and tangentially to the table so as to enter and emerge from the cloth upon the same side, a foot held stationary upon the head between the path of the needle and the arm with aperture 30 for the passage of the needle, the raceway P curved in a vertical plane and supported upon the head above the foot contiguous to the path of the needle and transverse to the same, a shuttle movable in the raceway with point adjacent to the 35 path of the needle, and means for reciprocating the shuttle in the raceway.

2. In a blind stitching machine, the combination, with the frame of the machine having a post, a goose-neck and a head carried thereby, and a feed-arm projected from the 40 post beneath the head and provided with a flat feed-table, of a needle-bar upon the head with means for oscillating it transversely to the feed-arm, a foot held stationary between the path of the needle and the feed-arm, a raceway supported upon the head above the foot contiguous to the 45 path of the needle and transverse to the same, a shuttle movable in the raceway with point adjacent to the path of the needle, and means for reciprocating the shuttle in the raceway, the feed-arm being pivoted upon the post and having a spring to press it normally upward, a screw 50 to vary the tension of the spring.

3. In a blind stitching machine, the combination, with the frame of the machine having a post, a goose-neck and a head carried thereby, and a feed-arm projected from the post beneath the head, of a needle-carrier oscillated upon 55 the head with a curved needle, a foot held stationary upon the head between the path of the needle and the feed-arm, a raceway supported upon the head above the foot contiguous to the path of the needle and transverse to the same, a shuttle movable in the raceway with point adjacent to the 60 path of the needle, means for oscillating the shuttle in the raceway, and means for oscillating the needle-carrier and curved needle alternately in different planes to form zigzag stitches, and for oscillating the needle-carrier continuously in the same plane when required to form a 65 straight line of stitches.

4. In a blind stitching machine, the combination, with the head of the machine having a curved needle with carrier to oscillate the same, of a raceway and shuttle supported upon the head above the path of the needle, and the 70 needle-carrier having a pivot-shaft reciprocated longitudinally, whereby the successive oscillations of the needle take place in different parallel planes, a work support, and said needle operating entirely above the work support to enter and emerge from the same face of the work, whereby 75 a blind stitch is formed.

5. In a blind stitching machine, the combination, with

the head of the machine having a curved needle with carrier to oscillate the same, of a raceway and shuttle supported upon the head above the path of the needle and the needle-carrier having a pivot-shaft with means to reciprocate the same longitudinally, whereby the successive oscillations of the needle may take place in different parallel planes, such means being constructed to hold the pivot-shaft from longitudinal movement when required, so as to oscillate the carrier continuously in the same plane to 80 form a straight line of stitches.

6. In a blind stitching machine, the combination, with the frame of the machine having a post, a goose-neck and a head carried thereby, and a feed-arm projected from the post beneath the head, of a needle-bar upon the head with a curved needle, means for oscillating it transversely to the feed-arm, a foot held stationary upon the head between the path of the needle and the feed-arm, a raceway divided into two sections and curved in a vertical plane, and the sections supported upon the head above the foot contiguous to the path of the needle and transverse to the same, a shuttle movable in the raceway with point adjacent to the path of the needle, and means for reciprocating the shuttle in the raceway once for each oscillation of the needle. 90

7. In a blind stitching machine, the combination, with the frame of the machine having a post, a goose-neck and a head carried thereby, and a feed-arm projected from the post beneath the head and provided with a flat feed-table, and feeding mechanism for propelling the cloth across the flat table transverse to the feed-arm, of a needle-bar upon the head carrying a curved needle, means for oscillating the needle transversely to the feed-arm and tangentially to the table so as to enter and emerge from the cloth upon the same side, a foot held stationary upon the head between the path of the needle and the arm with aperture 100 for the passage of the needle, the raceway P curved in a vertical plane and supported upon the head above the foot contiguous to the path of the needle and transverse to the same, and divided at the middle in the path of the needle to permit its passage and arranged with one corner contiguous to such path, a shuttle fitted to the raceway and tapered wholly toward the said corner to engage the loop of the needle-thread at such corner, and means for reciprocating the shuttle in the raceway. 105

8. In a blind stitching machine, the combination, with the frame-goose-neck, head, and a driving-shaft extended into the head, of a feed-arm projected below the head and supporting a cloth table, a bearing upon the head with rock-shaft mounted to oscillate and reciprocate therein, a needle-arm attached to the rock-shaft and provided with a curved needle, means for oscillating the rock-shaft to reciprocate the curved needle through the cloth, means for reciprocating the rock-shaft after each oscillation of the needle to shift the needle-arm and oscillate the needle in a different parallel plane, a raceway divided at the middle for the 110 passage of the needle and for the lateral movement of the needle in making zigzag stitches and arranged just above the path of the needle, and a shuttle fitted to the raceway with means to reciprocate the shuttle once for each oscillation of the needle. 115

9. In a blind stitching machine, the combination, with the head and a driving-shaft extended into the head and having a foot sustained upon the head with aperture for the tangential movement of the needle, of a cloth-table below the foot, a bearing upon the head, a rock-shaft fitted to oscillate and reciprocate in such bearing, a needle-arm attached to the rock-shaft with curved needle, means for oscillating the rock-shaft to reciprocate the curved needle through the aperture in the foot tangentially to the cloth-plate, a universal joint upon the end of the rock-shaft and a cam with connections to the driving-shaft and to said universal joint to reciprocate the rock-shaft once for each oscillation of the needle. 120

10. In a blind stitching machine, the combination, with the frame, goose-neck, head, and a driving-shaft extended into the head, of a feed-arm projected below the head and supporting a cloth table, a feeding device projected through the surface of the cloth table to feed the cloth transversely of the arm, a foot sustained upon the head with aperture for the tangential movement of the needle, a raceway suspended upon the head above the foot with shuttle movable 125

therein, means for actuating the shuttle, a bearing upon the head with rock-shaft fitted to oscillate and reciprocate therein, a needle-arm attached to the rock-shaft and carrying a curved needle with a movement through the aperture of the foot tangential to the feeding device, means for oscillating the needle-arm and curved needle, a cam and cam-shaft with gears connecting the same to the driving-shaft, the segment *g* oscillated by connection to the cam, a connection from the segment to the rock-shaft to reciprocate the same, and means to oscillate the rock-shaft, whereby the needle-arm and curved needle are oscillated in different parallel planes intermediate to the reciprocation of the rock-shaft.

11. In a blind stitching machine, the combination, with the frame, goose-neck, head, and a driving-shaft extended into the head, of a feeding-arm projected below the head and supporting a cloth table, a feeding device projected through the surface of the cloth table to feed the cloth transversely of the arm, a foot sustained upon the head

15 with aperture for the tangential movement of the needle, a raceway sustained upon the head above the foot with

shuttle movable therein, means for actuating the shuttle, a bearing upon the head with rock-shaft fitted to oscillate and reciprocate therein, and having a universal joint thereon, a needle-arm attached to the rock-shaft and carrying a curved needle with a movement through the aperture of the foot tangential to the feeding device, means for oscillating the needle-arm and curved needle, a cam and cam-shaft with gears connecting the same to the driving-shaft, the segment *g* oscillated by connection to the 25 cam, and having a slot extended across the axis of the segment, a pin adjustable in the slot from the axis of the segment to any outer point, and a link connected to such pin and to the universal joint upon the rock-shaft to reciprocate the same intermediate to the oscillations of the 30 needle.

In testimony whereof I have hereunto set my hand in the presence of two subscribing witnesses.

JOHN E. FEFEL.
